UNITED STATES PATENT OFFICE

HORATIO D. JONES, OF BROOKLYN, NEW YORK

EXTENSION SUPPORT FOR FLEXIBLE ELECTRICAL CONDUCTORS

Application filed September 24, 1924. Serial No. 739,536.

My invention relates to means for supporting flexible conductors, and the same has for its object more particularly to provide a simple, reliable and efficient support which will so hold the flexible conductor or cord of an electrically operated device that the same will not interfere with the operator of such device.

Further, said invention has for its object to provide a support of the character specified which is adapted to be carried by an electrically operated device and to project laterally outward therefrom to hold said conductor or cord out of the way of the operator or user of the device.

Further, said invention has for its object to provide a device of the character specified which serves to maintain the flexible conductor of an electric iron out of the way of the operator to permit of the unimpeded movement of said iron in different directions, and to prevent damage to said conductor.

Further, said invention has for its object to provide a device of the character specified in which the same is adapted for application to electric irons, or other electrical devices, of different types or makes.

Further, said invention has for its object to provide a device of the character specified in which the supporting member thereof is mounted for movement horizontally to permit of the yielding thereof when said electrically operated device is in use, or when said device comes into contact with the operator, or other person, or thing in its path.

Further, said invention has for its object to provide a device of the character specified in which the supporting member thereof for the flexible conductor automatically swings in accordance with the changes in the direction of movement of the iron to maintain the flexible conductor constantly out of the way of the operator and of the iron, and thereby to permit of the unimpeded travel of said iron, and to prevent injury to said conductor.

Further, said invention has for its object to provide a device of the character specified in which the supporting member for the flexible cord is secured to the attaching plug to permit of the attachment and removal of

said member with the plug without detaching the flexible cord from said member.

Further, said invention has for its object to provide a device of the character specified in which the supporting member thereof may be adjusted in accordance with the angle at which the attaching plug is secured to the electric iron, or other electrically operated device.

Other objects will in part be obvious and in part be pointed out hereinafter.

To the attainment of the aforesaid objects and ends my invention consists in the novel details of construction, and in the combination connection and arrangement of parts hereinafter more fully described and then pointed out in the claims.

In the accompanying drawings showing an illustrative embodiment of the invention—

Figure 1 is a side elevation showing one form of conductor supporting device constructed according to and embodying my said invention;

Fig. 2 is a plan thereof with parts broken away;

Fig. 3 is an enlarged detail side view of the inner portion of the device secured to an attaching plug;

Fig. 4 is a view thereof at right angles to that of Fig. 3; and

Fig. 5 is a sectional view thereof on the line 5—5 of Fig. 4.

Referring to the drawings, the supporting device is illustrated, by way of example, applied to an electric iron, although the invention may be applied to other electrically operated devices with which flexible conductors or cords are employed to permit of the moving of said electrically operated devices at will.

The electric iron 10 is provided with the usual socket or connecting member 11, commonly located near the heel of said iron. The socket 11 is adapted to receive the attaching plug 12 connected to one end of the flexible conductor or cord 13, the opposite end of the cord 13 being provided with the usual means to permit of the connection thereof with a suitable supply of electric energy. The conductor 13 is surrounded adjacent to

its point of connection to the plug 12 with the usual coiled flexible member 14 to prevent the conductor 13 breaking at said point of connection.

5 The conductor supporting device 15 is carried by the iron 10, or other electrically operated device, and projects laterally outwardly therefrom, preferably projecting outwardly horizontally from the rear end or heel 10 of the iron 10. The device 15 includes a supporting member 16, preferably of fairly heavy wire adapted to be somewhat flexible although sufficiently stiff to support the cord or conductor 13 in position above the table 15 or other surface on which the ironing is done.

10 The supporting member 16 is attached at the heel of the iron 10 by a clamping or attaching member 17 adapted to be secured to the attaching plug 12 by the fastening devices 18 connecting the ends of the clamping member 17 at one side of the plug 12. The member 17 includes resilient portions 19 engaging the opposite sides of the plug 12 to provide an extended engagement therewith, and is adapted to fit into the socket 11 to provide a firm engagement between the plug and the socket and between the clamping member 17 and the plug 12.

15 The supporting member 16 is attached to the clamp 17 at the opposite side thereof, which is also the side remote from the operator when using the iron. For this purpose an adjustable member 20 is preferably threaded into the nut 21 held in the recess 21^a in the clamp 17 to permit of the rotation or adjustment of said member 20 on a horizontal axis. The inner end portion 22 of the member 16, which is arranged at an angle to the body thereof, is pivotally disposed in an opening 23 through member 20 to permit of the member 16 swinging horizontally. A shoulder 24 on the portion 22 limits the downward movement thereof through the opening 23, and the end 24^a is split and spread 20 after the insertion of the member 16 to retain the same in place on member 20.

25 In use the member 16 extends outwardly horizontally and pivots around a vertical axis to permit of the swinging thereof in a horizontal plane. The device 15 being attached to the plug 12, it is necessary to adjust the pivot in each case to position the same vertically. In the type of iron illustrated the socket 11 is inclined relatively to the iron. 30 In other types of irons the socket is vertically or otherwise disposed. Irrespective of the angularity of the socket, the member 16 may be positioned to swing horizontally by rotating the member 20 to position the opening 23 vertically. After adjustment of the member 20 the same may be locked by a suitable device, such as the wing nut 25. The adjustable member 20 permits of the application of the device to irons of different types or makes.

35 At intervals along said member 16 upwardly

projecting double loops 26 are formed to receive between each pair of the same the flexible conductor 13 in order to support the latter at several separated points along the member 16. The loops 26 of each pair grip the conductor between them to retain the conductor on the member 16 while permitting of the ready insertion of said conductor, and removal thereof, as desired. The inner pair of loops 26 is spaced outwardly on member 16 beyond the end of the member 14 to permit of the connection of the conductor or cord 13 thereto to provide slack 27 in said conductor at the inner end thereof to permit of the swinging of said member 16.

40 It should be noted that the member 16 is pivoted at a point adjacent to the connection of the cord 13 to the iron 10, and preferably on the side of the plug 12 opposite that on which the operator stands when using the iron. The said member 16 extends outwardly horizontally a distance more than twice the length of the iron so that during the movement of the iron in different directions the trailing portions of the cord 13 beyond the outer end of the member 16 will be maintained out of the way of the iron so that the cord, or the insulation around the same, will not become injured or burned. By preference, the member 16 is made about 18 inches long. By arranging the member 16 horizontally and attaching the same to be carried by the iron adjacent to the point of connection of the cord 13 thereto, the latter may be attached to the member 16 without unduly flexing or bending the same to provide plenty of play in the portion 27 of said cord between the inner loops 26 and the plug 12 to permit of the swinging movement of said member 16.

45 After the device 15 is once secured to the plug 12 the same may be left thereon with the cord 13 secured in the loops 26, as the device 15 is readily removable with the plug 12 and replaceable in position therewith.

50 When the plug 12 is engaged with the iron 10, it may be necessary to adjust the member 20, as above described. After this adjustment is once made for a given iron the member 20 may be permanently clamped by the nut 25.

55 By reason of the construction and arrangement of the member 16 and the connection of the cord 13 thereto, the member 16 relatively swings automatically to positions indicated approximately in broken lines in Fig. 2, when the direction of movement of the iron 10 changes. When the iron is moved by the operator to the position α , Fig. 2, the member 16 relatively swings to assume approximately the position γ . When the iron is moved to reverse the position of the heel and toe thereof, as indicated at α , the member 16 assumes approximately the position γ , i. e. projects beyond the toe.

60 In each case the relative movement of the

member 16 is such as to keep the same out of the way of the operator so that the same will not touch the operator and annoy him. The flexible cord 13 also is maintained out of the way of the operator, and out of the way of the iron to prevent injury thereto. The cord is also always arranged to prevent the undue bending thereof, which might result in injury thereof. The automatic operation is rendered possible by the provision of the pivot as located for the member 16, and the same swings relatively to the iron 10 upon movement of the latter by reason of the outer attachment of the cord 13 carried thereby, which is fixed beyond the outer end of the member 16 to the local circuit.

The member 16 is sufficiently rigid or stiff to maintain the cord supported horizontally, and by reason of the material of which the same is composed, it is slightly flexible vertically; this flexibility being enhanced by the provision of the loops 26 which render one portion of the member 16 flexible relative to another portion. The loops 26 firmly retain the cord 13 in position during operation, and permit of the ready insertion thereof, and its removal, if desired.

Having thus described my said invention, what I claim and desire to secure by Letters Patent is:

1. A device of the character described comprising a flexible supporting member adapted to be carried at one end by an electrical device provided with a flexible conductor, and double loops arranged in parallelism substantially longitudinally of the supporting member formed at intervals along said member adapted to grip the conductor therebetween to hold said conductor in position upon said member, substantially as specified.

2. A device of the character described comprising an attaching member for securing the device in position, a supporting member for a flexible conductor pivotally connected to said attaching member for swinging movement horizontally, and means for adjusting said supporting member in a vertical plane relative to said attaching member, substantially as specified.

3. A device of the character described comprising a clamping member adapted to embrace an attaching plug, means for securing said clamping member in position upon said plug, a rotatable arm extending horizontally from said clamping member, a supporting member pivotally secured at one end to said clamping member and movable in a horizontal plane, means on said supporting member for securing a flexible conductor thereto, and means for securing said rotatable arm to adjusted position whereby to vary the angle of said supporting member in a vertical plane, substantially as specified.

4. A device of the character described comprising a clamping member adapted to em-

brace an attaching plug, means for securing said clamping member in position upon said plug, a rotatable arm extending horizontally from said clamping member, a supporting member pivotally secured at one end to said clamping member and movable in a horizontal plane, means on said supporting member for yieldingly retaining a flexible conductor in position upon said supporting member, and means for securing said rotatable arm to adjusted position whereby to vary the angle of said supporting member in a vertical plane, substantially as specified.

5. A device of the character described comprising a clamping member adapted for securing to an attaching plug, a screw revolvably secured to said clamping member and extending laterally therefrom, a nut on said screw for securing the same to adjusted position, a supporting member provided at intervals with registering pairs of loops to receive and retain a flexible conductor extending from said plug; said supporting member having an angular end pivotally secured in said screw whereby to sustain said supporting member in position and permit of the movement thereof in a horizontal plane, substantially as specified.

6. A device of the character described wherein is provided an attaching plug and a conductor extending therefrom, a means to support the conductor, which means comprises an attaching member having provisions for mounting the same on the plug and a supporting member adjustably mounted on said attaching member in each of two planes at approximately right angles to one another and means for securing said member to its adjusted positions.

7. A device of the character described wherein is provided an attaching plug and a conductor extending therefrom, a means to support the conductor, which means comprises an attaching member having provisions for mounting the same on the plug and a supporting member mounted on said attaching member with provisions for adjustment in each of two planes at approximately right angles to one another, said supporting member comprising an elongated rod-like element having double loops arranged in parallelism substantially longitudinally of the supporting member at intervals in its length, the axes of which loops lie transversely of the length of said element, said loops constituting holding clamps for said conductor.

Signed at the city of New York, in the county and State of New York, this 19th day of September, one thousand nine hundred and twenty-four.

HORATIO D. JONES.
